UNITED STATES PATENT OFFICE.

JOHN H. CUNTZ, OF HOBOKEN, NEW JERSEY.

WAVE-DETECTOR.

1,080,681.

Specification of Letters Patent. Patented Dec. 9, 1913.

Application filed October 1, 1903. Serial No. 175,292.

To all whom it may concern:

Be it known that I, JOHN H. CUNTZ, a citizen of the United States, residing at Hoboken, in the county of Hudson and State of New Jersey, have invented an Improvement in Wave-Detectors, of which the following description, in connection with the accompanying drawings, is a specification, like letters on the drawings representing 10 like parts.

My invention relates to improvements in systems of space telegraphy and particularly to those means employed for detecting or responding to electroradiant energy transmitted from a transmitting point to a receiving point.

My invention will be best understood from the following description taken in connection with the accompanying illustration of 20 one specific embodiment thereof, while its scope will be more particularly pointed out in the appended claims, it being understood that the selected embodiment herein described is submitted as illustrative only of 25 one form or species of the generic invention claimed.

In the drawings is diagrammatically represented a receiving station for receiving electroradiant manifestations from the 30 transmitting point, such receiving station being equipped with a simple form of my improved wave detector.

Referring to the drawings, *a* is an aerial or other receiving member connected to 35 ground at *b*, through the conductors *c* and *d*, the receiving circuit having a sensitive or detecting portion, *e*, interposed between the conductors *c* and *d*. The said portion *e* is herein formed by a moving mass having 40 suitable conductive properties and having a movement along a suitable path to give definiteness to the receiving circuit, yet having instability of the individual particles. These conditions are produced herein by 45 maintaining a flow of mercury or other fluid from the conduit *f* to the underlying receptacle *g*, the fluid being allowed to flow or drop through a suitably shaped nozzle at the end of the conduit *f*. Mercury is particularly desirable for this purpose since it 50 has but slight susceptibility to the chemical

effect of the atmosphere, possesses good conductive properties, and has both metallic and fluid characteristics, the latter permitting it to flow easily under the influence of 55 gravity and to form a conducting path in the manner described. It is to be understood however that my invention is not limited to the use of mercury or to the use of any substance necessarily possessing any 60 one or more of the characteristics of mercury, or to the manner in which the movement of the particles is effected. It is also to be understood that my invention is not limited to either the specific or general manner 65 in which the electrical instability of the circuit is produced or maintained; but that other means than those illustrated may be employed.

Referring again to the drawings, the fluid 70 which passes to the receptacle *g* is again elevated by the pump *h* to the reservoir *i*, which latter connects with the conduit *f*, where it is again available for the production or maintenance of the detecting portion 75 *e* of the receiving circuit. The pump *h* may be operated in any suitable manner, either as a result of the radiant energy transmitted, or from some external source, and either constantly or intermittently. By the 80 above described means, a continual circulation of the fluid is maintained and its progressive movement produced along the sensitive portion *e* of the receiving circuit. In order that the fluid in its movement may 85 offer a conductive path only through the stream *e*, and not through the pump *h* and the reservoir *i*, the outlet from the receptacle *g* may be made sufficiently large to cause definite interruptions in the flow 90 therefrom and in the electrical continuity of the stream thereat, or other means for causing intermittent flow from the receptacle *g*, or at another point or points in the circulation system, may be utilized for this 95 purpose.

A local circuit *j* connects a battery *k* in series with the sensitive portion *e* of the receiving circuit, any suitable detecting device, as a telephone, *l*, being employed in operative relation to the local circuit, as by inductively relating the same thereto through 100

the transformer *m*. A condenser *n* may be employed as shown, to increase the efficiency of the detecting circuits. The portion *e* of the stream may be connected in any suitable 5 way with the receiving circuit. I have shown the end of the conductor *d* as dipping into the fluid within the receptacle *g*; and the conductor *c* as connected to the fluid within the conduit *f*; but obviously, the de- 10 tails of these connections are immaterial.

The detecting portion *e* of the receiving circuit forms also a part of the local circuit *j*, and under normal conditions the electrical properties of the local circuit are sub- 15 stantially constant, providing no variations in the current conditions in the local circuit for the actuation of the detecting device *l*. On the receipt of a wave of electroradiant energy however, the detecting portion *e* of the receiving circuit has its conductivity altered, which in turn causes a sudden change in the current conditions through the local circuit, whereby the detecting device *l* is actuated. 20

25 Since the sensitive portion *e* of the receiving circuit is continually undergoing reformation, and that reformation tends to take place under renewed conditions of sensitivity to the electroradiant energy, the receiving circuit is self-restoring in its sensitive condition on the cessation of radiant energy. It is to be observed however that although the self-restoration is substantially immediate on the cessation of electroradiant 30 energy, yet, during the receipt of such energy, the self-restoration is slight; and that the reformation of the sensitive portion of the circuit is progressive. It will be obvious, furthermore, that although the mercury or other substances employed, which 35 constitute the sensitive portion *e* of the receiving circuit, are progressively moved into and out of the receiving circuit, momentarily forming a part thereof, yet the conditions 40 under which this movement takes place may be made substantially constant, so that relatively good and poor conductivities occur under substantially like conditions at all times. These conditions however, though 45 constant for any given adjustment of the apparatus, may be varied within wide limits, as desired, by the employment of suitable means for governing the character of the flow or movement of the particles at *e*. The 50 length and the cross-section of the portion *e* of the receiving circuit, as well as its rate of movement, may all be varied as desired. Various shaped nozzles may be employed to impart a different character of flow to the 55 sensitive portion of the receiving circuit, or instead of the effect of gravity, suitable mechanical means may be employed for effecting a flow of the liquid in any desired 60 direction.

The conductivity of *e*, and hence the current in the local circuit, may have widely different values at different times provided the changes are made gradually and slowly so as not to actuate the detecting device *l*. 65

The term conductivity is herein employed 70 in its broad sense, which ascribes to all bodies or substances conductivity differing only in degree. The conductivity of the elements under discussion may therefore at times be of the highest, or so low as to cause 75 practical interruption of the current there-through.

It is to be understood that my invention is capable of wide modification from the illustrative embodiment herein described, and 80 that the same is not limited to the details herein set forth.

Having described my invention, what I claim and desire to secure by Letters Patent is—

1. In a wave detector a detecting circuit composed in part of a progressively moving element normally of metallic conductivity, and means for maintaining continuous circulation thereof. 85

2. In a wave detector a detecting circuit composed in part of a continuously circulating element, normally of metallic conductivity, moving in a definite path in a continuous cycle. 90

3. A wave detector having detecting means comprising a circulating fluid stream normally of metallic conductivity. 95

4. A wave detector having detecting means including mercury in continuous circulation. 100

5. A wave detector having a liquid stream element normally of metallic conductivity and mechanical means for restoring the same to its original position. 105

6. A wave detector composed in part of a liquid element normally of metallic conductivity continuously moving in a path unconfined in part.

7. A wave detector having detecting means formed by a liquid stream normally of metallic conductivity. 110

8. A wave detector including a liquid of normal metallic conductivity which has a continuous stream movement in the same 115 general direction.

9. A self-restoring normally-metallically conductive fluid stream wave detector, the self-restoration of which is gradually effected through mechanical motion. 120

10. A wave detector of normal metallic conductivity self-restoring through its continuous bodily movement in the same general direction.

11. A wave detector having electrodes and 125 detecting means between the electrodes including a liquid conductor normally of metallic conductivity mechanically moving in

a stream from one electrode toward the other.

12. A wave detector having a detecting circuit composed in part of an element of 5 normal metallic conductivity continuously moving in the direction of the circuit.

In testimony whereof, I have signed my

name to this specification, in the presence of two subscribing witnesses.

JOHN H. CUNTZ.
